SHOE

David Levin, New York, N. Y.

Application November 30, 1937, Serial No. 177,261

2 Claims.

(Cl. 36—12)

My invention relates to an improvement in the construction of shoes and particularly to the securing of the sole to the upper. Among the objects are:

5 A shoe with the upper secured to the sole by thongs.

An open work between the sole and upper consisting of thongs.

An upper movably secured to the sole.

10 A self adjusting and fitting shoe upper.

A health shoe ventilated and self adjusting.

An attractive yet comfortable shoe. Thongs or ribbons as a means for securing the soles to the uppers.

15 I accomplish these and other objects by the construction herein described and shown in the accompanying drawing forming a part hereof in which:

Fig. 1 is a side view of my shoe.

20 Fig. 2 is an enlarged fragmentary detail.

Fig. 3 is a section at 3—3 Figures 1 and 2.

Fig. 4 is a fragmentary section at 4—4 Figures 1 and 2.

25 Figs. 5, 6, and 7 are fragmentary details of modification of thongs and their application.

Similar reference characters refer to similar parts throughout the several views of the drawing and in the specifications to follow:

The upper 1 is separated from the sole 2 by 30 the space 3 in which the thongs 4 unite and secure the upper to the sole. The space 3 may be crossed by thongs all around the edges 5 of the sole and 6 of the upper or may be provided only part way between the toe 7 and heel 8 as shown 35 in Figure 1 in which the thongs end at 9 leaving an open space 10 around and near the heel.

I have shown the upper 1 as having perforations 11 over its surface and a thong 4 as passing through many of the lower row of perforations 12. The upper 1 and sole 15 are laced together as follows: One end of the thong is passed inwardly through an aperture 12 in the upper. In order to form a loop 13, this end is brought outwardly below the edge of the upper and across 45 that portion 16 of the thong coming from below to said aperture 12, and then inwardly and upwardly on the interior of the shoe. This end is then passed outwardly through the next aperture 12 in the upper and downwardly (as shown 50 at 17) through the loop 13 and at the same time crosses the portion 16 of the thong. The thong is then shown as passing through the aperture 14 in the upper sole 15 and under said upper sole from one aperture 14 to another one end 16 passing rearwardly toward the heel and the other

end 17 passing forward toward the toe. The ends pass each other in opposite directions between the upper sole 15 and the lower sole 18 which conceals the thongs 4 between the upper and lower soles.

By the construction just described the thongs 4 may be laced in and out through the lower row of apertures 12 and the apertures 14 in the upper sole 15 continuously along one side of the sole and upper around the toe and along the other side to the point 9 and the thongs may yield to permit movement between the upper and the sole thereby adjusting the upper automatically to the foot of the wearer and at the same time affording ample ventilation to the foot. The portion 19 of the upper not secured to the sole near and around the heel provides a separate adjustment and freedom around the heel of the foot. The upper sole and lower sole may be secured to each other by the stitching 20 or otherwise.

In the modifications shown in Figures 5, 6 and 7 I have shown the thongs 4 connecting the upper 1 to the sole 2 in other ways than hereinbefore described. In Figures 5 and 6 the thongs 4 are shown as formed integral with the upper 1 and the ends are carried under the inner sole 21 to which they may be secured. In Figure 7 the thongs 4 are shown as being laced through the apertures 12 and held to the sole by being secured to the inner sole or between the insole and the sole 2. In either case as in the construction shown in Figures 1 and 2 inclusive the space 3 between the sole and upper is bridged by the thongs.

I have herein shown and described the construction of my shoe in detail and it is obvious after this disclosure to one skilled in the making of shoes that numerous modifications of my invention are apparent to suit the various conditions to which it is adapted in the manufacture of shoes. I therefore do not wish to be limited to the details herein disclosed as I may wish to depart therefrom within the scope of the appended claims which set forth my invention.

I claim:

1. In a shoe, an upper having apertures along its lower edge and a sole apertured along its edge separated from said upper by a space, and a thong laced across said space to secure said upper to the sole, the end of said thong passing from an aperture in the sole below upwardly and inwardly through an aperture in the upper then downwardly and outwardly forming a loop over said thong and inwardly and up-

wardly and through another aperture in said upper then outwardly and downwardly through said loop and across said thong and into another aperture in said sole.

8. 2. In a shoe, an upper having apertures along its lower edge and a sole apertured along its edge separated from said upper by a space, and a thong laced across said space to secure said upper to the sole, the end of said thong passing from an aperture in the sole below, upwardly and inwardly through an aperture in the upper and then downwardly and outwardly

forming a loop over said thong and inwardly and upwardly through another aperture in said upper then outwardly and downwardly through said loop and crossing said thong and into the next aperture in said sole, a lower sole, the ends of the thong passing in opposite directions between said sole and said lower sole and extending upwardly through said sole and through adjacent apertures in said upper thereby extending said lacing for a substantial distance 10 around the edges of said upper and sole.

DAVID LEVIN.
